Primary Examiner — Wan Laymon(74) *Attorney, Agent, or Firm* — Hayes Soloway P.C.**CLAIM**

The ornamental design for a bottle neck, as shown and described.

DESCRIPTION

FIG. 1 is a front view of a bottle showing our design, the back view being a mirror image thereof;

FIG. 2 is a top perspective view;

FIG. 3 is a top plan view; and,

FIG. 4 is an enlarged fragmentary front view.

The broken lines shown in the figures represent portions of the bottle neck that form no part of the claimed design.
